BED AND CYLINDER PRINTING PRESS

Calvert B. Cottrell, 3d, Westerly, R. I., assignor
to C. B. Cottrell & Sons Company, Westerly,
R. I., a corporation of Delaware

Application May 11, 1933, Serial No. 670,409

16 Claims. (Cl. 101—283)

My invention is directed, broadly, to novel means for bringing the bed and cylinder into printing coaction providing a sheet has been fed to the press and properly registered, said bed and cylinder remaining out of said printing coaction should a sheet fail to be fed to the press.

My invention more particularly consists in electrically controlled mechanical means for raising and lowering the impression cylinder, said mechanical means comprising a toggle lever, a differential gear for opening and closing the toggle lever to cause the raising and lowering respectively of the impression cylinder, and an electric brake for the differential gear, said brake being controlled by the bed as it reaches the limit of its printing stroke and by a light responsive device, as a photoelectric unit, as the bed reaches the limit of its non-printing stroke.

I have chosen to illustrate my invention in connection with the bed and cylinder printing press which forms the subject matter of my copending application filed February 2, 1933, Serial No. 654,855.

A practical embodiment of my invention is represented in the accompanying drawings, in which

Fig. 1 represents my improved bed and cylinder printing press in side elevation, the parts being shown in full lines in the positions they assume as the registered sheet is about to be taken from the feeder by the form bed grippers on the printing stroke of the bed, and in dotted lines in the positions they assume as the bed reaches the end of its printing stroke;

Fig. 2 represents a detail horizontal section taken in the plane of the line II—II of Fig. 1, looking in the direction of the arrows; and

Fig. 3 is a complete wiring diagram of the embodiment represented in Figs. 1 and 2.

The oscillating impression cylinder is denoted by 1 and its set of grippers by 2. The reciprocating bed is denoted by 3 and its form by 4. The sheet feeder, denoted by 5, is provided with a sheet stop 6, said feeder being located at one side of the impression cylinder 1.

The delivery which is located at the other side of the impression cylinder includes, in the present instance, a rotary sheet carrier 7, provided with a set of grippers 8 arranged to take the printed sheets from the grippers 2 of the impression cylinder and to deliver the sheets at the top of the rotary carrier to the coating endless tape carriers 9, 10.

The reciprocating form bed is provided with a set of tumbler actuated grippers 11 which operate on the printing stroke of the bed to take the

sheets from the feeder 5 after they have been registered and to transfer the sheets to the impression cylinder grippers 2 at the bottom of the cylinder, as shown, described and claimed in my said copending application filed February 2, 1933, Serial No. 654,855.

The several grippers may be operated in any well known or approved manner at the proper times, and their operating means are not shown and will not be specifically described herein.

Means are provided for normally lifting the impression cylinder away from its printing coaction with the form bed, said means in the present instance comprising expansion springs 12.

The electrically controlled mechanically operated means for causing the bringing of the bed and cylinder into and out of coaction is constructed, arranged, and operated as follows:

A toggle lever has its upper arms 13 pivoted at 14 to the frame and has its lower arms 15, carried by a rock shaft 16, mounted in the cross heads 17 of the cylinder lifting bars 18. The shaft 16 is provided with a depending arm 19 which is connected by a rod 20 to a crank 21 on the differential gear shaft 22. The differential gear is constantly driven from the drive shaft 23.

The shaft 24 of the differential gear is provided with a clutch mechanism drum 25 connected to the armature 27 of the electric brake 28. This electric brake 28 is connected through a circuit maker and breaker 29 by the circuit wires 30, 31, 34. The circuit maker and breaker 29 is in the form of a normally open switch having its arm 32 arranged in position to be moved

by a lug 33 on the bed 3 as the bed reaches the limit of its printing stroke, to close the circuit through the wires 30, 31, 34 for energizing the electric brake 28. The wires 30, 31 are also connected through a circuit maker and breaker 37 to a circuit wire 38 leading to a source of electric current supply not shown herein. The circuit maker and breaker 37 is a normally open switch, which circuit is open when the toggle lever is closed and is closed when the toggle lever is open.

The electric brake 28 is connected directly to a source of electric current supply, not shown herein, through the circuit wire 35. The electric brake 28 is also under the control of a light responsive device such, for instance, as a photoelectric unit which is in turn controlled by

the registry of the sheet on the sheet feeder 5 as is clearly shown in my copending application filed December 17, 1932, Serial No. 647,714, now Letters Patent No. 1,951,901, dated March 20, 1934. This photoelectric unit is connected

through the circuit line 46 to the side guide 47 of the sheet registering device, the operation of which is fully explained in my said Letters Patent 1,951,901. This photoelectric unit comprises, 5 generally, the following elements:

The photoelectric tube 38 is electrically connected to the photoelectric relay 39 of any well known or approved form. This photoelectric tube 38 is positioned beneath the feed table 5 in 10 the path of a beam of light projected from the lamp 40. This relay 39 is electrically connected to the electric brake 28 through the circuit wires 41, 42. The circuit wires 41, 42 are also connected through a circuit maker and breaker 36 to a normally open switch, which circuit is closed when the toggle lever is closed, and open when the toggle lever is open. This relay 39 is also electrically connected to a source of electric current supply, not shown herein, through the circuit wires 20 44, 45.

In operation: As the bed 3 reaches the limit of its non-printing movement and presupposing that a sheet has been fed and registered so that it is in position to be taken by the grippers 11 of 25 the bed, the registry of the sheet will cut off the beam of light from the lamp 40 of the photoelectric unit, thereby closing the contactor switch 48 and completing a circuit through the electric brake 28, thus causing the brake to hold the differential shaft 24 against rotary movement. This will permit the constantly driven shaft 23 30 to rotate the differential shaft 22 to move the toggle lever 13, 15 in the direction to lower the impression cylinder 1 into printing position. As 35 the toggle lever moves in this direction it will open the switch 36 and the circuit through the wires 41, 42, thus deenergizing the electric brake 28 as the differential shaft is rotated one-half a revolution, the freeing of the differential shaft 40 24 rendering the drive between the shafts 23 and 22 ineffective. Also as the toggle lever 13, 15 moves in the said direction it will close the switch 37.

As the bed reaches the limit of its printing movement its lug 33 will engage the switch arm 45 32, thus closing the circuit through the circuit maker and breaker 29 and the circuit wires 30, 31, thereby energizing the brake and causing it to again hold the differential shaft 24 stationary. This will permit the drive shaft 23 to rotate the differential shaft 22 to break the toggle lever, thus permitting the expansion springs 12 50 to raise the impression cylinder out of its printing position. As the toggle lever 13, 15 is opened 55 it will again open the switch 37, thus deenergizing the electric brake 28, thereby releasing the differential shaft 24 and rendering ineffective the connection between the drive shaft 23 and crank shaft 22.

It will be understood that if no sheet is fed to the form bed grippers 11 on the printing stroke of the bed the electric brake 28 will remain deenergized, thus allowing the springs 12 to hold the impression cylinder 1 in its raised position out of 60 printing coaction with the form bed.

It is evident that various changes may be resorted to in the construction, form and arrangement of the several parts without departing from the spirit and scope of my invention, and 65 hence I do not intend to be limited to the particular embodiment herein shown and described, but

What I claim is:

1. In a bed and cylinder printing press, an impression cylinder, a reciprocating form bed, a

sheet feed controlled photoelectric unit, means normally separating the bed and cylinder, and means for bringing the bed and cylinder into and out of printing coaction, said means including a lever, a differential gear for operating it and an electric brake for the differential gear, controlled by the bed and said photoelectric unit. 5

2. In a bed and cylinder printing press, an impression cylinder, a reciprocating form bed, a sheet feed controlled photoelectric unit, means normally lifting the cylinder from the bed, and means for bringing the cylinder into and out of printing coaction with the bed, said means including a lever, a differential gear for operating it and an electric brake for the differential gear, 10 controlled by the bed and said photoelectric unit. 15

3. In a bed and cylinder printing press, an impression cylinder, a reciprocating form bed, a sheet feed controlled photoelectric unit, means normally separating the bed and cylinder, and 20 means for bringing the bed and cylinder into and out of printing coaction, said means including a lever, a differential gear for operating it, an electric brake for the differential gear and a circuit maker and breaker for the brake, operated by the 25 bed at the end of its printing stroke, said brake being operated by the photoelectric unit at the end of the non-printing stroke of the bed.

4. In a bed and cylinder printing press, an impression cylinder, a reciprocating form bed, a sheet feed controlled photoelectric unit, means normally lifting the cylinder from the bed, and means for bringing the cylinder into and out of printing coaction with the bed, said means including a lever, a differential gear for operating 30 it, an electric brake for the differential gear and a circuit maker and breaker for the brake, operated by the bed at the end of its printing stroke, 35 said brake being operated by the photoelectric unit at the end of the non-printing stroke of the 40 bed.

5. In a bed and cylinder printing press, an impression cylinder, a reciprocating form bed, a sheet feed controlled photoelectric unit, means normally separating the bed and cylinder, and 45 means for bringing the bed and cylinder into and out of printing coaction, said means including a toggle lever, a differential gear for opening and closing it and an electric brake for the differential gear, controlled by the bed and said photoelectric unit. 50

6. In a bed and cylinder printing press, an impression cylinder, a reciprocating form bed, a sheet feed controlled photoelectric unit, means normally lifting the cylinder from the bed, and 55 means for bringing the cylinder into and out of printing coaction with the bed, said means including a toggle lever, a differential gear for opening and closing it and an electric brake for the differential gear, controlled by the bed and 60 said photoelectric unit.

7. In a bed and cylinder printing press, an impression cylinder, a reciprocating form bed, a sheet feed controlled photoelectric unit, means normally separating the bed and cylinder, and 65 means for bringing the bed and cylinder into and out of printing coaction, said means including a toggle lever, a differential gear for opening and closing it, an electric brake for the differential gear and a circuit maker and breaker for the 70 brake, operated by the bed at the end of its printing stroke, said brake being operated by the photoelectric unit at the end of the non-printing stroke of the bed.

8. In a bed and cylinder printing press, an 75

- impression cylinder, a reciprocating form bed, a sheet feed controlled photoelectric unit, means normally lifting the cylinder from the bed, and means for bringing the cylinder into and out of printing coaction with the bed, said means including a toggle lever, a differential gear for opening and closing it, an electric brake for the differential gear and a circuit maker and breaker for the brake, operated by the bed at the end of its printing stroke, said brake being operated by the photoelectric unit at the end of the non-printing stroke of the bed.
9. In a bed and cylinder printing press, an impression cylinder, a reciprocating form bed, a sheet feed controlled photoelectric unit, means normally separating the bed and cylinder, and means for bringing the bed and cylinder into and out of printing coaction, said means including a lever, a differential gear for operating it and an electric brake for the differential gear, controlled by the bed and said photoelectric unit, said brake being also under the control of the said lever.
10. In a bed and cylinder printing press, an impression cylinder, a reciprocating form bed, a sheet feed controlled photoelectric unit, means normally lifting the cylinder from the bed, and means for bringing the cylinder into and out of printing coaction with the bed, said means including a lever, a differential gear for operating it and an electric brake for the differential gear, controlled by the bed and said photoelectric unit, said brake being also under the control of the said lever.
11. In a bed and cylinder printing press, an impression cylinder, a reciprocating form bed, a sheet feed controlled photoelectric unit, means normally separating the bed and cylinder, and means for bringing the bed and cylinder into and out of printing coaction, said means including a lever, a differential gear for operating it, an electric brake for the differential gear and a circuit maker and breaker for the brake, operated by the bed at the end of its printing stroke, said brake being operated by the photoelectric unit at the end of the non-printing stroke of the bed, said brake being also under the control of the said lever.
12. In a bed and cylinder printing press, an impression cylinder, a reciprocating form bed, a sheet feed controlled photoelectric unit, means normally lifting the cylinder from the bed, and means for bringing the cylinder into and out of printing coaction with the bed, said means including a lever, a differential gear for operating it, an electric brake for the differential gear and a circuit maker and breaker for the brake, op-
- erated by the bed at the end of its printing stroke, said brake being operated by the photoelectric unit at the end of the non-printing stroke of the bed, said brake being also under the control of the said lever.
13. In a bed and cylinder printing press, an impression cylinder, a reciprocating form bed, a sheet feed controlled photoelectric unit, means normally separating the bed and cylinder, and means for bringing the bed and cylinder into and out of printing coaction, said means including a toggle lever, a differential gear for opening and closing it and an electric brake for the differential gear, controlled by the bed and said photoelectric unit, said brake being also under the control of the said toggle lever.
14. In a bed and cylinder printing press, an impression cylinder, a reciprocating form bed, a sheet feed controlled photoelectric unit, means normally lifting the cylinder from the bed, and means for bringing the cylinder into and out of printing coaction with the bed, said means including a toggle lever, a differential gear for opening and closing it and an electric brake for the differential gear, controlled by the bed and said photoelectric unit, said brake being also under the control of the said toggle lever.
15. In a bed and cylinder printing press, an impression cylinder, a reciprocating form bed, a sheet feed controlled photoelectric unit, means normally separating the bed and cylinder, and means for bringing the bed and cylinder into and out of printing coaction, said means including a toggle lever, a differential gear for opening and closing it, an electric brake for the differential gear and a circuit maker and breaker for the brake, operated by the bed at the end of its printing stroke, said brake being operated by the photoelectric unit at the end of the non-printing stroke of the bed, said brake being also under the control of the said toggle lever.
16. In a bed and cylinder printing press, an impression cylinder, a reciprocating form bed, a sheet feed controlled photoelectric unit, means normally lifting the cylinder from the bed, and means for bringing the cylinder into and out of printing coaction with the bed, said means including a toggle lever, a differential gear for opening and closing it, an electric brake for the differential gear and a circuit maker and breaker for the brake, operated by the bed at the end of its printing stroke, said brake being operated by the photoelectric unit at the end of the non-printing stroke of the bed, said brake being also under the control of the said toggle lever.

CALVERT B. COTTRELL, 3RD.
